UNITED STATES PATENT OFFICE.

ARNOLD S. WEBSTER, JR., OF CAMDEN, NEW JERSEY.

EXPLOSIVE-ENGINE.

1,096,141.

Specification of Letters Patent. Patented May 12, 1914.

Application filed January 28, 1913. Serial No. 744,617.

To all whom it may concern:

Be it known that I, ARNOLD S. WEBSTER, Jr., citizen of the United States, and resident of Camden, county of Camden, and 5 State of New Jersey, have invented an Improvement in Explosive-Engines, of which the following is a specification.

The object of my invention is to provide explosive engines, more especially employed 10 in automobiles, with auxiliary heating devices, preferably for employing electrical energy as the source of heat, for maintaining the water jacket of the cylinders in a warm condition to prevent freezing of the water 15 therein when the machine is standing and the engine out of operation.

Heretofore much damage has been done 20 by the cooling water in the jacket of the engine cylinders becoming frozen and the expansion thereof rupturing the jackets of the cylinders, producing leaks which are difficult of repair and mostly requiring new cylinders as replacement of the injured members. By use of my invention, this 25 danger is overcome, as a sufficient quantity of heat may be radiated from the heater upon the outside of the cylinder jackets to maintain the water therein above the freezing point; and as the necessity for this pre- 30 caution only exists in very cold weather and when the automobile is required to stand in the open air for a long period of time, the cost of the heating would only apply to those short periods of use.

My invention consists in surrounding the 35 water jacket portions or cylinders of the explosive engine with an electric or other heater and combining therewith a suitable 40 source of electric or other heat generating energy and controlling means. As this heater is itself inclosed by the hood over the engine, the heat radiated upon the engine cylinders remains confined to a large extent 45 within the hood, and thereby reduces the size of the heater necessary very materially to what would be required if the hood were employed. I also provide the front of the heater with removable or door portions which in cold weather, are kept closed; but 50 in warm weather said doors are retained open or removed to provide opportunity for the usual air circulating fan driving the cooling air directly upon the engine cylin-

ders, the heater case in such instances acting as a guide for the air to insure its flowing in 55 a positive manner over all of the cylinders and just when it is needed. The heater is preferably made in parts for more easy detachment and removal when necessary, or desired for repair or other reason.

My invention also comprehends other details of construction, which, together with the features above specified, will be better understood by reference to the drawings, in which:—

Figure 1 is a side elevation of a portion of an automobile embodying my invention and having the front portion of the engine hood cut away; Fig. 2 is a plan view of the same with the engine hood removed; Fig. 3 is a sectional plan view of the electric heater removed from the engine, the section being taken on line $\alpha-\alpha$ of Fig. 1 and broken across to shorten its length; and Fig. 4 is vertical cross section through one of the side 75 portions of the electric heater taken on line $y-y$ of Fig. 3.

2 is the main frame or chassis of the automobile, 3 is the usual cooler, 4 is the engine hood and 7 is the dash board. The engine 5 is of the explosive type and of any construction which employs water jackets for 80 its cylinders; said engine being provided with a crank case 8. Air may be circulated over the engine cylinders by the usual circulating fan 6. These parts may be of any 85 usual construction.

Surrounding the engine cylinders 5, I provide an electric heater, consisting of the two side portions 9, 9, having flanged ends 90 12 by which they may be united into annular form by the thumb bolts 13, (Fig. 3). This electric heater may rest upon the crank case and be provided with lugs 11 through which clamping screws 10 may pass for firmly securing it to the crank case.

The rear end of the heater may be semi-circular, as indicated at 9^b, but the forward end is preferably made polygonal in shape, as at 9^a, the flattened portions corresponding to doors 17 above them, as indicated in Figs. 1 and 2; the purpose of which doors is to more readily control the air passing over the engine in summer and in very cold weather providing means for shutting off 105 excessive draft from the circulating fan 6.

The electric heater may be of any suitable construction, the form shown comprising the outer metallic wall or case bent over at top and bottom (Fig. 4) and lined with asbestos or other suitable refractory non-conducting lining 14. The heating wires are indicated at 15 and may be wound around upper and lower insulator rods 16 of any suitable construction. In practice, one terminal of the wires 15 of each half 9 of the heater may be connected to the heater case and thereby be grounded to the engine, the other terminals of the wires 15 extending from the case as insulated wires 23 and connecting with a socket 22; said wires 23 may be connected in parallel. Current may be supplied from a storage or other battery 26 to the electric heater by the wire 25, having a plug 24 which fits the socket 22 on the dash board 7. The other circuit 27 from the battery is grounded to the engine and in that way is in circuit with the other terminals of heater wires 15. In place of the battery 26, a dynamo or other source of electric energy may be provided, as the source of current is immaterial to my invention. By withdrawing the plug 24, the heater will be cut out of action.

The doors 17 are hinged at 18 to the heater casing parts 9, and when closed, they meet about the fan shaft and may be secured by the locking bolt 21 (Fig. 2). When in this position, the main draft of the fan 6 is cut off from the engine, and this may be the case in very cold weather and especially where the engine is run slowly and not employed continuously for any long period of time. At other times, the doors 17 are swung outward as indicated in dotted lines in Fig. 2, and clamped against stop braces 19 by clamping bolts 20. In this position of adjustment, the fan 6 may force the air freely upon the engine cylinders and the doors guide it directly upon the cylinder; and the heater case insures the air passing over all of the cylinders and escaping upwardly, and thereby effecting a more thorough cooling.

I have shown my invention in the form most practical of application, but I do not restrict myself to the details, as these will be modified in many ways to suit the different types of engines and automobile framing, as well as to adapt my invention to the particular uses to which it may be put, it in no way being restricted to use on automobiles. My invention, moreover, is adapted for use by employment of any auxiliary heater surrounding the water jacketed portions of the cylinders for heating them externally when the engine is out of operation and hence I do not restrict my invention to the employment of an electric heater, though I prefer the same.

Having now described my invention, what

I claim as new and desire to secure by Letters Patent, is:—

1. The combination of an explosive engine having a water jacket, with a heating device arranged about the water jacket of the engine for providing heat to prevent freezing of the water within the water jacket when the engine is out of operation said heater being made in detachable parts, clamps for securing said parts together, and means for securing the heater to the engine.

2. The combination of an engine having a water jacket, with a heater separate from and surrounding the water jacket of the engine said heater being open at the top, one end of the heater provided with movable portions providing access for air thereto, and a draft fan arranged in front of the opening so provided.

3. The combination of an engine having a water jacket, with a heater separate from and surrounding the water jacket of the engine said heater being open at the top, one end of the heater being provided with hinged doors, means for holding the doors in open or closed position, and a draft fan arranged in front of the doors, the construction being such that when the doors are open they act as guides for the air currents from the fan.

4. The combination of an explosive engine having a water jacket, with a heating device arranged about and out of direct contact with the water jacket of the engine, said heating device providing means for causing radiant heat to be projected upon the water jacket of the engine from opposite sides, said heating device being arranged to provide a space on each side of the engine for circulating air, and said heater being open at the top and having an opening at the front of the engine, whereby cool air is admitted to the space between said heater and engine, and circulates therethrough on each side of the engine and passes out of the top when the engine is in operation.

5. The combination of an explosive engine having a water jacket, an electric heater surrounding the water jacket of the engine and providing an air space between the heater and water jacket, said heater being open at the top, means for clamping the heater detachably in position upon the engine, a source of electric energy, and means for controlling the current from the source of electric energy to the electric heater.

6. The combination of an explosive engine having a water jacket, an electric heater partially encircling the sides of said water jacket so as to radiate heat thereupon, and forming with said jacket a space for circulating air, a source of electric energy, and means to removably secure said heater in position with respect to said water jacket.

7. The combination of an explosive engine

having a water jacket, an electric heater partially encircling the sides of said water jacket so as to radiate heat thereupon, and forming with said jacket a space for circulating air, and a source of electric energy, said heater being open at the top and having an opening at the front of said engine whereby cool air is admitted to the space

between said heater and said engine, circulates therethrough and passes out at the top. 10
In testimony of which invention, I hereunto set my hand.
